UNITED STATES PATENT OFFICE

92,566

DESIGN FOR AN EAR-MUFF

Solomon D. Abraham, Milwaukee, Wis., assignor to Comfort Ear-Lap Co., a copartnership consisting of Solomon D. Abraham and Charles M.
Apple, Milwaukee, Wis.

Application September 18, 1933, Serial No. 49,282

Term of patent 14 years

To all whom it may concern:

Be it known that I, SOLOMON D. ABRAHAM, a citizen of the United States, and a resident of Milwaukee, in the county of Milwaukee and State of Wisconsin, have invented a new, original, and ornamental Design for an Ear-Muff, of which the following is a specification, reference being had to the accompanying drawing, forming part thereof.

I claim:

The ornamental design for an ear-muff, as shown.

In testimony that I claim the foregoing I have hereunto set my hand at Milwaukee, in the county of Milwaukee and State of Wisconsin.

SOLOMON D. ABRAHAM.
